COUPON BOOK

Anthony S. Kalinowski, Chicago, Ill., assignor to
 Rand McNally & Company, a corporation of
 Illinois

Application August 4, 1937, Serial No. 157,396

1 Claim. (Cl. 283—62)

This invention relates to a coupon book, and more particularly to a book of the type adapted to have therein a long continuous coupon strip to be torn off at intervals.

One feature of this invention is that it provides an improved coupon book of the type wherein a long continuous coupon strip is used; another feature of this invention is that the stripper member used to tear off a portion of the coupon may have the coupon more readily inserted under it; yet another feature of this invention is that it is so arranged that a scale on the cover accurately determines the amount of coupon to be torn off; still another feature is that the stripper member is so fastened to the book as to present no exposed corners; other features and advantages of this invention will be apparent from the following specification and the drawing, in which:

Figure 1 is a plan view of one side of a coupon book embodying this invention; Fig. 2 is a similar view of the other side of the book; Fig. 3 is a view of the book in open position, part of the continuous strip coupon being broken away to show ticket coupons therebeneath; Fig. 4 is a fragmentary plan view of the cover with the coupon strip removed from beneath the stripper member; Fig. 5 is a fragmentary detailed view of the attachment of the stripper member; and Fig. 6 is a perspective view of the stripper member prior to its being attached to the book.

Coupon books have been known which employ long continuous strip coupons, and which use a stripper member and a cooperating scale to determine the amount of coupon to be torn off. Such books have been open to several objections, however. One common difficulty is that the stripper member is fastened at both ends to the book and the coupon strip must be threaded beneath it with considerable difficulty. Another defect of such books is that the stripper member is generally found on the back portion of the book, the same portion to which one end of the coupon strip is attached, so that the fold or crease at which the cover joins the back is interposed between the stripper member and a large portion of the measuring scale. This causes difficulties in precise measurement of the amount of coupon to be torn off, since after some use the junction may either stretch, compress, fall in double folds, or otherwise change the relative distance between the graduations on the scale and the upper or tearing edge of the stripper member.

The present invention obviates these and

other defects by placing the stripper member on the same portion of the book on which the scale is located, the cover, so that nothing short of actual destruction of the cover will throw the distances out of their correct relation. The stripper member, moreover, is only fastened to the cover at one end, and is preferably formed of resilient metal so that the other end may be easily lifted to slide the coupon strip in from one side. The stripper is also attached to the book in a manner which prevents sharp corners being present, which might be likely to cut the pockets or hands of the user.

In the particular embodiment of this invention illustrated herewith a coupon book 10 is illustrated as having a back portion 11 and a cover portion 12 foldably joined, as at the creased portion 13. This enables the book to be laid open, as illustrated in Fig. 3, or to be kept closed, as in Fig. 2, for insertion in the pocket or the like.

The back 11 of the book has attached to it on the inside thereof ticket coupons 14, here illustrated as a plurality of one cent coupons. While there may be several pages of such coupons, they are all bound to the back of the book at one end, preferably that next the creased or folded portion 13.

Lying over these ticket coupons is a long continuous coupon strip 15, which is several times the length of the back portion of the book, and is preferably attached thereto at one end. This coupon 15 is adapted to be folded back and forth upon itself in order to be contained within the book, and is here shown as a coupon divided into five cent portions, the strip being of sufficient length to have a value of ten dollars. It will be noted that the coupon strip is numbered with respect to value on each side thereof, these numbers running in opposite directions. That is, referring to Figure 3, the numberings on the left continuously decrease from ten dollars to the end of the strip fastened to the book, not here shown; while the numberings on the right hand side increase in similar steps of five cents each.

The cover 12 has mounted thereon a stripper member 16 here shown as a relatively long thin piece of resilient metal. The stripper member has one end bent back upon itself with the corners turned up to form prongs 17 and 18. The center portion of this turned back end is punched up to form a third prong 19. The corners forming the prongs 17 and 18 are bent at approximately an angle of 45 degrees with each of the sides forming a corner as may be clearly seen from Figures 5 and 6. The stripper mem-

ber is attached to the cover 12 at one end thereof by placing the bent back portion on the outside of the cover, forcing the prongs 17, 18 and 19 through the cover material, generally of card-board, and bending them down on the inside as illustrated in Figure 5. The stripper member is preferably attached so that it lies parallel to the folds 13, which is the junction of the back 11 and cover 12, and fairly close thereto. It is also preferably fastened on the lefthand edge, speaking with respect to Figures 3 or 4.

The cover 12 is also provided with a scale 20, here shown on the lefthand margin of the inside thereof. This scale should have its point of origin at the upper or tearing edge of the stripper member 16, and should be graduated to correspond to the long coupon strip used. In the present case, as may be seen from Figure 4, it is graduated in five cent intervals up to one dollar. The outside of the back and cover also have a scale printed thereon. Consideration of Figures 1 and 2 will show that this starts at the upper or free end of the cover, and continues to the free end of the back of the book.

25 The book is particularly adapted for use as a railroad or gasoline station coupon book, for example, and may be very conveniently used. Where it is desired to remove a portion of the coupon strip 15, as for example a portion representing 75¢, it is only necessary to flip open the cover, and slip the free end of the strip 15 beneath the stripper member 16. This may be easily done by lifting the free or righthand edge of the stripper slightly and slipping the coupon strip in from that side. Then the strip is pulled up until its top edge registers with the desired indication on the scale, as for example the 75¢ indication as illustrated in Figure 3. The stripper member would then be held tightly against 40 the coupon strip and the cover, as by the thumb of one hand, and the portion of the coupon strip thereabove would be torn off along its upper edge. The coupon strip would then be withdrawn from beneath the stripper, allowed to drop back into its folds, and then become closed. Where the amount desired ended in odd cents, one or more of the ticket coupons representing one cent each could be torn off to supplement the portion of the coupon strip 15.

45 50 The fact that the coupon strip is withdrawn from beneath the stripper member and allowed

to fall back into its regular creases or folds permits the book to be closed without any bulging or disarrangement of the coupon strip. Placing of the stripper member on the same portion of the book as the measuring scale of twenty, here 5 the cover, results in elimination of any errors which might otherwise be introduced by the folded or creased portion 13 serving to join the back to the cover. The particular arrangement of the stripper member, moreover, in addition to 10 providing very easy placement of the coupon strip thereunder, so fastens it to the book that no free corners are left to catch in the pockets or hands of the user.

If it is desired to tear off a larger amount of the 15 coupon strip than is shown on the scale 20 on the inside of the cover, either of two courses may be followed. The first or preferable course is to pull up the strip to the last scale mark on the 20 inside of the cover, here \$1.00, tear that amount off, and then pull up as much more as is necessary. If it is desired to tear it off in one portion, however, the strip may be pulled right on up past the 25 top or free end of the cover 12, and down the back thereof until its end registers with the scale 25 mark desired, as for example, \$1.75. The desired portion would then be torn off, using the free or upper end of the cover 12 as a tearing edge.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as permissible, in view of the prior art.

I claim:

A book comprising hingedly connected back 40 and front covers, a strip guiding and tearing bar, said bar immovably located on the inner face of the front cover adjacent the hinge line and extending transversely of said front cover, and an elongated strip secured to the back cover adjacent 45 the hinge line and extending beneath said bar over the inner face of the front cover, said front cover carrying on its inner face a scale for use in determining portions of said elongated strip to be torn off.

ANTHONY S. KALINOWSKI.
